FLOTATION MACHINE

Randall P. Akins, Denver, Colo.

Application November 7, 1933, Serial No. 696,929

7 Claims. (Cl. 209—168)

This invention relates to a flotation machine for the concentration of ores and has for its principal object the provision of a machine of this character in which the rising column of air will efficiently act as the agitating medium for the pulp and provide a circulating current which will effectively bring the air into intimate contact with all of the ore particles.

Another object is to so construct the tank that the rising column of bubbles will be continuously forced toward the froth overflow to rapidly and continuously clear the froth from the machine.

A further object is to provide an air dispersion medium of a type which will prevent water from entering the air boxes, either while operating or during shut downs, and which will be so constructed as to assist in the propulsion of the gangue toward the discharge of the machine.

Other objects and advantages reside in the detail construction of the invention, which is designed for simplicity, economy, and efficiency. These will become more apparent from the following description.

In the following detailed description of the invention reference is had to the accompanying drawings which forms a part hereof. Like numerals refer to like parts in all views of the drawings and throughout the description.

In the drawings:

Fig. 1 is a cross section through the improved flotation machine, taken on the line 1—1, Fig. 5.

Fig. 2 is a detail face view of the upper baffle board.

Fig. 3 is a detail face view of the moveable baffle board.

Fig. 4 is a face view of the impeller.

Fig. 5 is a longitudinal section, taken on the line 5—5, Fig. 1.

Fig. 6 is a detail plan view of the air dispersion plate.

Fig. 7 is a cross section through the dispersion plate taken on the line 7—7, Fig. 5.

The invention comprises a relatively long spitz-kasten or tank 10. The bottom of the tank is formed with a long, relatively narrow, rectangular section, or channel as shown at 11. Above the channel 11, the front wall 12 of the tank flares outwardly at an angle of approximately 45° terminating in a froth overflow lip 13, in front of which the usual froth launder 14 is positioned. The back wall of the tank also flares outwardly, preferably at a steeper angle as shown at 15, thence extends upwardly as shown at 16; and thence inwardly as shown at 17 to a

horizontal top board or hood 18, which extends over and above the channel 11.

The upper area of the tank 10 is divided laterally into a series of cells by means of lateral partitions 19 which terminate a considerable distance above the channel 11. Below each of the lateral partitions 19 is an air partition 20 which divides the channel 11 into a series of air chambers 21. The top of each air chamber 21 is covered by means of a perforated plate 22.

It is desired to call special attention to the fact that the plates 22 are arranged in successive steps, that is, each plate is lower than the preceding plate, as the discharge extremity of the tank 10 is approached. A feed box 23 is positioned at the head end of the tank and opens thereto through a feed opening 24. A tailings discharge pipe 25 opens from the rear end of the tank at a lower level than the lowermost plate 22. Air is fed to the air chambers 21 from an air header 26 which communicates with each air chamber through an independent air pipe 27, each of which is controlled by a valve 28. A froth board 41 is spaced from the end wall of the tank 10 immediately above the last air partition 25. The latter is also spaced from the end wall to form a settling chamber 41 for the tailings outlet. Drain nipples 48 extend through the bottom of each air chamber 21, and are closed by means of suitable plugs 49.

In each cell an upper baffle board 29 is placed. The upper baffle boards extend downwardly from the hood 18 substantially to or slightly below the pulp level. The baffle boards 29 are perforated as shown in Fig. 2, preferably with a series of round perforations 30, and a second series of elongated perforations 31. Immediately below the baffle board 29 is a moveable baffle board 32 which rests at its extremities in socket members 33 positioned against the partitions 19. A third, inclined baffle board 34 is placed between the board 32 and the rear tank wall 16, the board being inclined toward the back at its top.

In use, the tailings discharge pipe 25 is turned upwardly at the extremity of the tank a sufficient distance to maintain the solution level therein at the desired point, preferably just below the froth lip 13, as indicated in Fig. 1. Air is supplied under the proper pressure to the air chambers 21 and issues through the dispersion plates 22 into the solution, arising therein in the form of bubbles. The pulp is fed into the feed box 23 and flows into the first cell and from there, into the succeeding cells below the partitions 19. The remaining pulp and gangue dis-

charges into the tailings chamber 41, thence into the tailings discharge pipe 25 where it rises and overflows the top thereof.

The air arising through the screens 22 passes 5 through the pulp, collecting the metallic values therefrom and elevating them in a rising column of bubbles. This rising column creates an upward current in the solution which strikes the inclined baffle boards 32 and 34, and is directed 10 by these boards rearwardly and upwardly against the forwardly inclined back 17. The forwardly inclined back 17 directs the froth forwardly constantly urged by the rising column of bubbles at the rear of the tank. This forwardly moving 15 froth passes through the perforations 30 and 31 in the baffle board 29 and onward to the froth overflow 13. A froth scraper 35 may be provided at this point to assist in passing the froth over into the launder 14, although the machine has 20 been found to operate very satisfactorily without a scraper.

Naturally a quantity of pulp, gangue and solution will be carried upwardly with the rising column of bubbles. This material will be deflected 25 by the baffle board 29 so that it will descend along the forward face of the baffle 32, which will prevent it from interfering with the rising column of bubbles. The inclined front board 12 will return this descending material over the dispersion 30 plates 22 from whence it will again be carried upwardly adjacent the rear wall of the tank. Thus all particles of the pulp will be subjected to and travel with the rising column of air bubbles several times during their passage through 35 each cell.

This whirling action imparts a spiral line of travel throughout the length of the tank 10 to all of the solid particles therein. As they reach the partition 19 of each cell they are carried beneath 40 the partition and will rise in the next cell. The coarse, heavy, non-floatable material will be carried along each dispersion plate 22 by the spiral current and will fall to the next succeeding plate throughout the length of the machine.

45 It is desired to call particular attention to the movable baffle 32. This baffle is provided with a series of perforations 42 along its upper edge so as to allow the surface current and bubbles to pass. It can be swung to any desired position 50 so as to regulate the rate of circulation in the cell to a point of maximum recovery for the particular ore being treated.

It is desired to call particular attention to the dispersion medium or plate 22 which is shown in 55 detail in Figs. 6 and 7. This consists of a relatively thin plate of non-corrosive material through which a series of narrow, staggered, slots are pierced in such a way as to raise the material about each slot on the upper surface of 60 the plate giving it a corrugated effect. This causes the slots to have a wider opening at the bottom than at the top which prevents them from packing or filling with material. It has been found that a plate of this construction will automatically seal itself should the supply of air be 65 cut off so that the pulp will not leak through and enter the air chambers 21. This sealing effect is accomplished by the fines or slimes settling over the entire surface of the plate automatically.

The machine as thus far described will operate efficiently and satisfactorily with a high recovery of values on the usual feed. It might be desirable however in some installations to provide a mechanical impeller in the first cell imme-

diate in front of and below the feed opening 24 to act as an emulsifier or conditioner or spumer for the entering pulp.

Such a device is illustrated in cell of Fig. 4 and preferably comprises a vertical shaft 36 suspended in vertical bearings 37 and terminating immediately above the dispersion plate 22. This shaft may be rotated from a suitable motor 38 through a belt drive 39. On the bottom of the shaft 36, is an upwardly forcing impeller 40. 10 Spaced a short distance above the impeller 40 is a downwardly forcing impeller 41. The incoming pulp from the opening 24 falls upon the impeller 41 and is forced downwardly against a rising column of solution and air from the impeller 40. 15 These two impacting columns contact and are forced violently outward in a sheet from between the two impellers, creating an effective emulsification of the pulp which greatly increases the effectiveness of the action of the remaining 20 cells.

The impellers 40 and 41 are preferably formed with an annular, conical, outer band 44 supported upon the extremities of a series of inclined vanes 43 as shown in detail in Fig. 4. The construction 25 causes the solution to spread as it leaves the impeller and creates maximum agitation.

If desired a lever 50 (see Fig. 1) may be mounted over each cell and connected by means of a connecting rod 51 with the moveable baffle 32. 30 The lever may be held in any desired position by means of a suitable toothed sector 52. This allows ready and convenient adjustment of the angularity of the baffle 32.

It will be noted that the tailings discharge pipe 35 25 exits from the tank below the top of the lowermost perforated plate 22. This effectively prevents sand from building up on the bottom of the tank over the orifices in the perforated plates. It also allows the entire solution and pulp content to be drained from the tank and, as it drains, 40 it will flow with cascading effect from one perforated plate to the next so as to wash the plates clean.

The slotted openings 31 in the baffle 29 allow 45 wood chips and other debris to pass through the baffle and over the froth lip. The pulsating effect of the solution eventually aligns all chips with one or more of these slotted openings. It will be noted that the hooded top 18, in combination 50 with the froth baffle 19, forms an air chamber above the pulp. The rising air creates a compression in this chamber which causes the compressed air to blow through the perforations 30 and 31 and, in so doing, it blows the froth toward 55 the discharge.

The lateral partitions 19 prevent intermingling of the rising mineral of one cell with the rising mineral in the adjacent cells and thereby allows the machine to be used to obtain a classifying effect by proper adjustment of the air valves 28. In use, it has been found that practically all of the lead in an ore may be floated in the first cell; the copper in the next cells; and the magnetite iron in the last cells, dropping the sulphide 65 iron to the tailings discharge, thus obtaining clean classification as well as a concentrate.

It is desired to call attention to the fact that it is not necessary to lift the heavy sand particles during their progress through the machine, as 70 there are no interfering partitions adjacent the perforated bottom plates. This allows free passage of the sand straight through the machine with the assistance of gravity.

While a specific form of the improvement has 75

been described and illustrated herein, it is desired to be understood that the same may be varied, within the scope of the appended claims, without departing from the spirit of the invention.

Having thus described the invention, what is claimed and desired secured by Letters Patent is:—

1. A flotation machine comprising: a relatively long tank; a longitudinal air channel in the bottom of said tank; a series of air partitions dividing said air channel into a series of air chambers; a perforated member covering each of said chambers; a forwardly inclined front wall in said tank above said channel terminating below the solution line in said tank; a rear wall in said tank formed to extend in a general forward direction, said rear wall terminating above the solution line in said tank; and a baffle board positioned above said perforated medium and below the solution level in said tank, said baffle board being inclined so as to direct rising material toward said rear wall, said baffle board being hingedly supported so that its angular position may be varied at will.
2. A flotation machine comprising: a relatively long tank; a longitudinal air channel in the bottom of said tank; a series of air partitions dividing said air channel into a series of air chambers; a perforated member covering each of said chambers; a forwardly inclined front wall in said tank above said channel terminating below the solution line in said tank; a rear wall in said tank formed to extend in a general forward direction, said rear wall terminating above the solution line in said tank; and a baffle board positioned above said perforated medium and below the solution level in said tank, said baffle board being inclined so as to direct rising material toward said rear wall, the upper edge of said baffle board being perforated.
3. A flotation machine comprising: a relatively long tank; a longitudinal air channel in the bottom of said tank; a series of air partitions dividing said air channel into a series of air chambers; a perforated member covering each of said chambers; a forwardly inclined front wall in said tank above said channel terminating below the solution line in said tank; a rear wall in said tank formed to extend in a general forward direction, said rear wall terminating above the solution line in said tank; a downwardly extending perforated baffle board extending from the forward extremity of said rear wall downwardly adjacent the solution line in said tank; and a second baffle board positioned below the solution level in said tank, said second baffle board being movably mounted so that it may be brought below said first baffle board when desired.
4. A flotation machine comprising: a tank; an air chamber formed in the bottom of said
5. A flotation machine comprising: a relatively long, narrow, box-like channel having an open top; a perforated plate closing the top of said channel; a front wall extending upwardly and forwardly from one side of said channel; a rear wall extending upwardly the other side of said channel, thence forwardly over said channel, so that both said front wall and said rear wall terminate above and on the same side of said channel, said walls enclosing a tank, said front wall terminating at the solution level and said rear wall terminating above the solution level in said tank; a perforated froth baffle extending downwardly from the forward extremity of said rear wall substantially to the solution level of said tank; and a baffle board positioned below and extending downwardly from said first baffle over and spaced from said inclined front wall.
6. A flotation machine comprising: a relatively long, narrow, box-like channel having an open top; a perforated plate closing the top of said channel; a front wall extending upwardly and forwardly from one side of said channel; a rear wall extending upwardly the other side of said channel, thence forwardly over said channel, so that both said front wall and said rear wall terminate above and on the same side of said channel, said walls enclosing a tank, said front wall terminating at the solution level and said rear wall terminating above the solution level in said tank; a perforated froth baffle extending downwardly from the forward extremity of said rear wall substantially to the solution level of said tank; and a baffle board positioned below and extending downwardly from said first baffle over and spaced from said inclined front wall, said baffle board being hingedly supported so that it may be inclined if desired.
7. A flotation machine comprising: a tank; an air channel in the bottom of said tank; a perforated plate covering said channel; a front wall in said tank extending forwardly and upwardly from the forward side of said channel and terminating in an overflow lip; a rear wall in said tank extending upwardly and forwardly from the rear side of said channel; and a baffle board positioned above said plate and inclined to direct rising material toward said rear wall.

RANDALL P. AKINS. 60
